UNITED STATES PATENT OFFICE

RALPH C. HYDE, OF LOS ANGELES, CALIFORNIA, ASSIGNOR TO CLAUDE NEON ELECTRICAL PRODUCTS CORPORATION, LTD., OF WILMINGTON, DELAWARE, A CORPORATION OF DELAWARE

SUPPORTING AND SPACING MEANS FOR GASEOUS DISCHARGE TUBES

Application filed May 7, 1930. Serial No. 450,589.

This invention relates to a device intended for supporting and spacing a luminous gaseous discharge tube from a mounting board or backing.

5 The mounting of a luminous gaseous discharge tube, such as the neon tubes which are employed in advertising signs requires the use of means for holding the different portions of the tube definitely spaced from 10 the backing plate. A considerable number of such spacing means is required and it is the primary object of the present invention to provide a simple form of bracket and co- 15 operating spacing posts for this purpose.

15 A further object of the present invention is to provide a combination of mounting bracket and spacing post for use with a gaseous discharge tube in which the post and bracket are both of simple and inexpensive 20 construction and in which the post and bracket are so formed that they may be readily and rapidly assembled and locked together.

25 The present invention together with various further objects and advantages thereof will best be understood from the description of a preferred form or example of a device embodying the invention. For this purpose there is hereafter described, with reference to 30 the accompanying drawings, the preferred form of device embodying the invention.

In the drawings:

Figure 1 is a drawing showing the bracket in place against a backing plate for a gaseous discharge tube with the post of the bracket engaging the tube in accordance with the manner of utilizing the bracket in practice.

40 Figure 2 is a section on the line 2-2 of Figure 1.

Figure 3 is a section on the line 3-3 of Figure 2.

Figure 4 is a view of the spacing post.

45 Referring to the drawings, 2 generally indicates a part of a gaseous discharge tube such as the familiar neon tubes used in advertising signs. The tube 2 is mounted in front of a plate 3 and must be spaced a definite distance from such plate, for which pur-

pose the device constituting the present invention is employed.

The device includes a bracket member 4 which is stamped out of sheet metal and is provided with a base or foot portion 5 which is intended to lie flat against the plate 3 and is provided with an opening 6 by which attaching means, such as screws 7, may be utilized for holding the same clamped against the plate 3. The bracket is further provided with ears 8 turned upwardly at right angles to the foot portion 5 and curved around, as indicated in Figure 3, to form a split socket. There is also provided an indentation 9 or other projecting means in the split socket thus formed which is adapted for making engagement with threads on a post or spacing member.

10 indicates a post-like spacing member which is formed of insulating material and is usually of glass or other fragile material, and the same is enlarged at its upper end, as indicated at 11, to form a head which is provided with a grooved seat 12. The lower portion of the post 10 is threaded, as indicated at 13, and adapted to engage the indentation 9 in the socket so that it may be screw threaded thereto. The post member is further provided with a longitudinal slot 14, as shown in Figure 4, leading from the lower end upwardly.

In use the bracket is secured to the plate 3 by the screw 7, or other suitable means, and then the post 10 is inserted in the spring-like socket formed by the curved ears 8, the indentation 9 or other projection of the socket passing through the slot 14. This permits the post to be rapidly placed in position. By turning the post relative to the bracket the indentation or other projection 9 engages the thread 13 on the post and forces the post against the backing plate 3, and the post is firmly held and locked in the operating position.

15 The tube 2 is then laid against the socket 12 on the post and tied by suitable means 16 to the post 10.

It is understood that the embodiment of the invention described herein is only one of the many embodiments this invention may

take, and I do not wish to be limited in the practice of the invention, nor in the claims, to the particular embodiment set forth.

I claim:

1. A device for mounting luminous gaseous discharge tubes upon and in spaced relation to a backing plate comprising a bracket member having a foot portion and a split socket portion integral therewith and turned at right angles to the foot portion, the socket having a thread engageable projection and a post member providing a seat for the tube, the post member being threaded for engagement with the projection of the socket, and a longitudinal slot in the post member through which the projection of the socket may be passed when the post is inserted into the socket.

2. A device for mounting luminous gaseous discharge tubes upon and in spaced relation to the backing plate comprising a post member of fragile insulating material, having threads at its lower end and having a socket for engagement with a tube at its upper end, a sheet metal bracket for supporting said post member at right angles to a backing plate, said bracket member comprising a foot portion adapted for attachment to the backing plate and a socket portion formed by curved ears extending substantially at right angles to the foot portion, the socket being provided with means for engaging the threads of the post member, the post member having a longitudinal groove adapted to align with the thread engaging means of the socket member to permit the post member to be axially slid into the socket.

3. A device for mounting luminous gaseous discharge tubes upon and in spaced relation to a backing plate comprising a bracket having a foot portion to be secured in contact with the backing plate and having a tubular socket formed on said foot, the longitudinal axis of the socket extending at right angles to the plane of the foot portion, a post member providing a seat for the tube, the post member being formed of insulating material and having a threaded portion thereof insertable in said socket, a projection on said socket extending inwardly thereof to engage said threads, said threads being cut away to form a longitudinal slot through which the projection on the socket may be passed when the post is inserted in the socket.

4. A device for mounting luminous gaseous discharge tubes upon and in spaced relation to a backing plate comprising a bracket attachable to said backing plate and having a socket formed therewith, a projection formed upon and extending inwardly of said socket and a post member including a portion insertable in said socket and having means thereon engageable with said projection to hold said post in said socket, a portion of the surface of said post being cut away to

permit insertion of said post in said socket free of engagement by said projection and a seat formed on said post for receiving said tube, said seat being disposed at such angle relative to said projection that the post must be rotated in said socket to align the seat with said tube.

Signed at Los Angeles, California this 29th day of April 1930.

RALPH C. HYDE.
